CLAIM

The ornamental design for a holder for writing instruments, as shown and described.

DESCRIPTION

FIG. 1 is a perspective view of a holder for writing instruments showing our new design;

FIG. 2 is a front elevational view thereof;

FIG. 3 is a rear elevational view thereof;

FIG. 4 is a top plan view thereof; and,

FIG. 5 is a bottom plan view thereof.

FIGS. 2 through 5 have been drawn to a reduced scale with respect to FIG. 1.
